UNITED STATES PATENT OFFICE.

LEONARD A. CREMER, OF PORTLAND, OREGON, ASSIGNOR OF ONE-HALF TO HARRY SEMLER, OF PORTLAND, OREGON.

DENTURE PRESS.

Application filed December 28, 1926. Serial No. 157,490.

My invention relates to a press for the commercial manufacturing of artificial dentures and consists primarily of a cylinder, a closure for said cylinder, with means to facilitate the removal and attachment of the closure to the cylinder, a heat supplying element for the cylinder, a release valve and a pressure indicator associated with the cylinder, a stationary and an adjustable element associated with the closure having means exteriorly thereof for applying mechanical pressure to the elements and flask engaging means associated with the stationary and adjustable elements, and a dial indicator indicating the relative position of the movable element and means to maintain the stationary and the movable elements in alignment.

A further object of my invention consists in providing a denture press for the manufacturing of artificial dentures, consisting of a plurality of flask holders, means for applying heat and pressure during the manufacturing process and means for indicating the pressure and the temperature, and the relative locations of the supporting and pressure applying elements.

A still further object of my invention consists of a new, novel and efficient means for the manufacturing of artificial dentures, consisting of related elements for quantity production of artificial dentures that will be uniform in density and uniform in accuracy.

With these and incidental objects in view, the invention consists in certain novel features of construction and combination of parts, the essential elements of which are set forth in the appended claims, and a preferred form of embodiment of which is hereinafter shown with reference to the drawings which accompany and form a part of this specification.

In the drawings:—

Fig. 1 is a side elevation of my assembled device.

Fig. 2 is a top plan view of the mechanism illustrated in Fig. 1.

Fig. 3 is a longitudinal, cross section, taken on line 3—3 of Fig. 2, looking in the direction indicated.

Fig. 4 is a longitudinal, cross section view, taken on line 4—4 of Fig. 2, looking in the direction indicated.

Fig. 5 is a fragmentary, sectional, side ele-

vation, taken on line 5—5 of Fig. 4, looking in the direction indicated.

Fig. 6 is a cross section view, taken on line 6—6 of Fig. 3, looking in the direction indicated.

Fig. 7 is a cross section view, taken on line 7—7 of Fig. 3, looking in the direction indicated.

Like reference characters refer to like parts throughout the several views.

I preferably form the primary section of my pressure tank 1, cylindrical in form, and place a head 2, in the lower section of the same and secure the extending walls 3 of the head, to the primary wall 1 of the tank by any suitable means, as by riveting or by welding, or by any other suitable means; pockets 4 being disposed in either side of the head for the reception of aligning rods 5 and 6. Aligning rods 5 and 6 engage with the pockets 4 of the head and are secured on their upper ends to the removable closure 7, which has a downwardly projecting flange 8 adapted to engage on the inner side of the pressure tank and having a groove formed therein to receive the upper end of the pressure tank element 1. The closure head 7, has projecting ears 9 and 10 for the retention of the pivotal pin 11 and the primary pressure tank has a band 12 disposed about its outer upper periphery and is secured to the primary tank 1 by any suitable means, as by welding or riveting, and ears 13 and 14 project outwardly therefrom and are in registerable alignment with the ears 9 and 10. Ears 13 and 14 are in spaced relationship with each other, to permit of the engagement of the threaded member 15 therebetween that is in hinged relationship with the pin 11. An adjusting thumb nut 16 having a collar 17 disposed thereupon is in threaded relationship with the threaded member 15, and engages the underside of the ears 9 and 10 to apply the initial pressure between the closure 7 and the pressure tank 1. A pressure hand wheel 18 engages the shank 19 which is in threaded relationship with the closure 7, as indicated in Fig. 3. A gland nut 20 maintains a steam tight joint between the shank 19 and the closure 7 by the insertion of suitable packing material within the space 21, disposed about the shank 19. Packing should also be inserted within the space 22 disposed be-

90

95

100

105

tween the band 12 and the closure 7, to maintain a steam tight joint at that location also. Disposed on the under side of the closure 7 are two pairs of outwardly extending supporting elements 23 and 24, having a pocket 25 associated therewith, into which the head 26 of the flask support 27 is made to engage. The flask supports having inwardly extending lugs 28 upon which the supporting plate 29 is made to engage and upon which the flask containing the artificial denture rests. Disposed upon the lower end of the threaded spindle or shank 19, is a head 30 having its side members 31 and 32, the same being secured together at the bottom by cross member 33. Inwardly extending lugs 34 are oppositely disposed upon the side members 31 and 32, the object of which is to engage with the upper side 20 of the flask containing the artificial denture. Guide lugs 35 are disposed upon the outside of the side members 31 and 32 and engage about the guide rods 5 and 6 and are in slidable relation therewith, the object of 25 which is to maintain the members in alignment and to prevent the skewing of the flask members having pressure applied therebetween.

In the use of my new and improved device 30 a quantity of water is placed within the tank, the closure 7 is made fast to the tank; heat is applied to the heat element 36. To prevent the development of undue pressure within the tank a blow off valve 37 is associated with the closure and a temperature gauge 38 is also associated with the closure 7 to determine the amount of temperature developed within the tank. When the proper temperature has been developed to 40 soften and make pliable the blank from which the artificial denture is to be made, pressure is then applied to the hand wheel 18, the amount of longitudinal movement imparted to the shank 19 may be indicated by 45 the pointer 39 in registering alignment with the graduated surface upon the shank 19.

An outside shell 40 may be placed adjacent the band 12 and having an outwardly extending flange 41 disposed upon the lower side thereof. To maintain the band 40 in spaced relationship with the primary tank 1, a suitable annular band 42 is placed between the primary tank 1 and the band 40. The band 40 may be made of copper or other suitable material that will take and maintain a polished surface to increase the appearance of the device.

While the form of mechanism herein shown and described is admirably adapted to fulfill the objects primarily stated, it is to be understood that it is not intended to confine the invention to the one form of embodiment

herein shown and described, as it is susceptible of embodiment in various forms, all coming within the scope of the claims 65 which follow:

What I claim is—

1. A device of the character described embodying a heat resisting vessel including a cover removably secured thereto, removable flask supports pendant from said cover normally residing within said vessel, plates carried by said supports and one below the other, side members vertically shiftable relative to said plates, including relatively stationary rods forming guides for said side members, said side members being each provided with individual means projecting above individual plates adapted for bearing upon flasks resting thereupon when said side members are lowered, and screw means extending through said cover for raising and lowering said side members. 75 80

2. In a denture press, a boiler, a cover therefor including means for removably securing the cover to the boiler, flask supports, said flask supports being in the nature of upright bars or rods each detachably secured by its upper end to the inner side of the aforesaid cover, a multiple of horizontally 90 disposed, vertically spaced plates, each forming a support for a denture flask supports, clamping members residing above and movable toward each plate and in cooperation therewith forming means for clamping a 95 flask resting on each of said plates, and means extending through said cover for moving said clamping members as aforesaid. 85

3. In a denture press, a heat resisting vessel including a cover removably secured thereto, a multiple of plates each forming a flask support supported from the inner side of said cover and spaced one below the other, a shank threaded through said cover, a head upon the lower end of said shank, 100 a pair of spaced side members extending downwardly from said head, inwardly extending lugs formed upon each side member, one upon each side member being spaced above each plate aforesaid, and moving thereto when said shank is threaded downwardly through said cover; a pair of vertical rods each forming a guide for one of the aforesaid side members and preventing its movement about the vertical axis of the 110 aforesaid shank, means for manipulating said shank for the purpose of lowering said side members, whereby each of the aforesaid lugs may be caused to bear upon a flask resting upon one of the aforesaid plates toward 115 which each of said lugs are caused to move, and means for indicating the limit of downward movement of said side members. 120~

LEONARD A. CREMER.
